BATHTUB SLIPPER

Charles J. Jesnig, Newtown Square, Pa.

Application May 7, 1938, Serial No. 206,576

7 Claims. (Cl. 36—8.1)

My invention relates to bath slippers intended for use by persons bathing in a tub and designed to reduce danger of slipping in the tub.

One of the purposes of my invention is to 5 mount vacuum cups on the sole of a bath slipper not only upon the ball and heel but upon a filled out section beneath the instep of the foot, so that flat footed engagement with the bottom of the tub will provide maximum protection against 10 slippage.

A further purpose is to cushion a bath slipper beneath the instep of the foot to an extent slightly in excess of a straight line from the ball of the foot to the heel so that with the deeper compression of the additional instep cushioning the bearing of the sole and heel of a bath slipper will 15 be substantially uniform.

A further purpose is to cushion the instep of a bath slipper and the ball and heel of the foot, the 20 cushioning being deeper under the instep than under the ball and heel, and to mount vacuum cups in the surface thus formed.

A further purpose is to provide a nearly plane 25 cushioned sole for a bath slipper having vacuum cups spread over it and with slightly projecting cup mouths, so that when pressure is placed on the sole by the wearer and the projections about the mouths of the cups are compressed, there will be a substantially uniform engaging surface 30 except for the interior of the cups.

I prefer to illustrate my invention by a single 35 form only selecting a form which is not only practical and effective but to advantage illustrates the principles thereof.

Figure 1 is a side elevation of a bath slipper 40 free from pressure but upon the foot of the wearer.

Figure 2 is a bottom plan view of the slipper of Figure 1.

Figures 3 and 4 are sections upon lines 3—3 and 4—4 through the slipper of Figure 2.

Figure 5 is a perspective front view of a laced 45 slipper and foot.

In the drawing similar numerals indicate like parts.

The very considerable difficulty in avoiding 50 injury in bath tubs, due to the bather slipping in the tub, has placed a premium upon any measure which offers safety.

The problem is best approached through the use of a slipper or other device fastened to the foot because it is always in protective position. The present invention is directed to securing a maximum grip of a slipper against the bottom 55 of the tub and a minimum of difference in this

grip with alternating positions of the foot with respect to the tub.

I have chosen to show a conventional garter top 10 and a laced top 11 only. Other forms of fastening than by the snap fasteners 12 or lacings 13 indicated by the drawing are of course available and are well known. The top may be cut out between the required points of attachment to the sole provided that the sole be properly secured to the foot against wobbling or slippage 10 of the foot. The word slipper is intended to be generic and to cover sandals and other informal foot coverings.

The sole of the slipper is intended to be resilient and may be made largely of rubber. The 15 cups 14, 15, 16, and 17 are shallow vacuum cups having annular surfaces about their rims which are compressible and which facilitate formation of a vacuum when the foot presses the cup against a tub bottom and brief but effective 20 maintenance of the vacuum while the pressure is applied. Because the cups must be air tight they are preferably of solid rubber but they need not be of pure rubber.

The annular contacts 18 preferably project 25 slightly beyond the adjacent surface 19 of the remainder of the sole of the slipper. There is not the same reason for the remainder of the sole of the slipper being solid as in the case of the vacuum cups and the annular rings and this 30 sole 19 may consequently be formed of solid rubber or of any other resilient material which reasonably grips the surface of a tub bottom when wet, which is otherwise appropriate for slipper sole use and which compresses and expands well under variations in pressure. It 35 might be of sponge rubber for example.

Union with the vacuum cups is required in order that the entire tread may act as a unit in holding against slippage and in order that 40 there may be no failure of the cups by reason of tearing away from the adjacent portions of the sole.

For convenience treating the material as rubber, the rubber not only extends over the greater 45 part of the heel and sole but is filled more, of course, at the inside of the instep than at the outside, so as to project beyond a plane joining the outer ball and heel surface of the slipper; with the thought that the greater depth of rubber at the instep will provide a greater extent of compression for the same weight than will be true of the ball and heel portions of the slipper. As there will be greater depth of material at the 50 inner side of the instep than at the outer side, 55

likewise the greatest initial convexity or outward curvature of the rubber at the instep in longitudinal section will occur on the inside of the foot, away from the observer in Figure 1 than in the outer part of the foot.

5 When the weight of the wearer is set upon the foot in the tub the compression at the instep, particularly at the inside of the instep will be greater than that of the other portions along the 10 tread of the slipper and the compression will result in a conformation of the lower part of the slipper agreeing with that of the surface of the tub against which it is placed, and substantially flat when the user is standing in the middle of 15 the width of the tub.

With the greater compression in the instep portion of the foot than at the ball and heel, the expansion of this compressed instep portion when the bather rocks slightly on the ball of the foot 20 will cause the rubber at the instep to continue for a short distance, contact with the tub bottom notwithstanding tilting of the foot. This will result in contact of more than just the ball of the foot with the surface of the tub even when 25 the heel has been lifted slightly from contact with the tub bottom, giving a longer and better tub contact than would otherwise be available.

For the same reason contact of the instep portion of the tread of the slipper against the bottom of the tub is not released immediately when the ball of the foot begins to lift from contact 30 with the bottom of the tub.

Because there is much more tendency of the 35 foot to slip laterally toward the outside of the foot and the side of the tub adjacent to it than toward the center of the tub and because the foot of the wearer is normally nearer to the side of the tub to the outside of the foot than to the opposite side of the tub the additional and "follow 40 up" contact of this relative swelled inner instep portion of the tread offers a special advantage.

It is intended that the compression of the rims of the vacuum cups shall be such that they will 45 compress to a point back of the normal uncompressed surface of the sole or heel of the shoe in order that there may be compression of the entire sole, including the instep portion, and heel, when the user stands flat-footedly within the bottom of the tub.

50 It will be evident that the bathing slippers may be manufactured in quantity to fit the normal instep with special sizes having additional or less thickness at the inside of the instep for the use of wearers having higher or shallower insteps.

55 It will be evident that my bathing slipper offers arch support benefits at the time when the wearer is in need of them because he is not wearing his normal shoes.

60 In view of my invention and disclosure variations and modifications to meet individual whim

or particular need will doubtless become evident to others skilled in the art to obtain part or all of the benefits of my invention without copying the structure shown, and I, therefore, claim all such in so far as they fall within the reasonable spirit and scope of my invention. 5

Having thus described my invention, what I claim as new and desire to secure by Letters Patent is:

1. A device for preventing slippage to be worn 10 on the foot having a tread of compressible material normally when uncompressed projecting further outwardly under the instep than under the ball and heel and compressible into approximately a plane under the weight of the wearer. 15

2. A device for preventing slippage to be worn on the foot having a tread normally of outwardly convexed, longitudinal vertical section from the heel past the instep and over the sole, the convex portion being freely compressible to approximately a plane by the weight of the wearer. 20

25 3. A device for preventing slippage to be worn on the foot, comprising a compressible tread adapted to fit the ball, heel, and instep of the wearer having a greater compressible depth at the inside of the instep than elsewhere and normally when uncompressed fuller at the inside of the instep than at the ball and heel and means for holding the tread to the foot of the wearer.

30 4. A device for preventing slippage to be worn on the foot comprising a resilient tread portion extending under the inside of the instep of the foot thicker at the instep than elsewhere, projecting downwardly at the instep, compressible approximately into a plane defined by the sole 35 and heel and covering the sole and heel, vacuum cups located in the tread including one beneath the instep and means for holding the tread to the foot.

40 5. In a device for preventing slippage to be worn on the foot a resilient tread portion including an arch support projecting downwardly under the instep of the foot to an extent beyond the sole and heel and there compressible by the weight of the wearer substantially into a plane with the sole and heel, vacuum cups located in the sole 45 and beneath the instep and means for holding the tread to the foot.

50 6. A device for preventing slippage to be worn on the foot comprising a tread and backing material of rubber filled out under the instep more on the inside than on the outside and far enough so that a longitudinal vertical section through the inside of the tread shall be convex downwardly.

55 7. A bath contrivance adapted to be worn on the foot and including a tread covering the ball, heel and instep of the foot having vacuum cups molded therein the tread being of outwardly convexed longitudinal section.
